UNITED STATES PATENT OFFICE.

DONALD BARNS MORISON, OF HARTLEPOOL, ENGLAND.

APPARATUS FOR WITHDRAWING AERATED VAPOR AND CONDENSATE FROM STEAM-CONDENSERS.

1,160,943.

Specification of Letters Patent.

Patented Nov. 16, 1915.

Application filed August 31, 1914. Serial No. 859,481.

To all whom it may concern:

Be it known that I, DONALD BARNS MORISON, a subject of the King of Great Britain and Ireland, residing at Hartlepool, in the county of Durham, England, have invented Apparatus for Withdrawing Aerated Vapor and Condensate from Steam-Condensers, of which the following is a specification.

When air is withdrawn from a main condenser by a steam jet which discharges into an auxiliary surface condenser in which the steam is condensed by cooling water that is not suitable for use in the boilers and from which the air is discharged by an air pump, the heat in the steam from the steam jet is lost.

This invention relates to improvements in steam condensing apparatus working under vacuum wherein aerated vapor is withdrawn from a main condenser by a steam jet and is discharged into a receiver in which the steam from the steam jet is condensed by water such as boiler feed water.

The object of the invention is to provide improvements in apparatus of the kind referred to in order to obtain effects by temperature whereby the size of the pump or pumps and the necessary driving power can be reduced, the arrangement being such that the heat in the steam from the steam jet and in the vapor from the condenser is usefully absorbed by boiler feed water; and whereby the air pump is enabled to deal with a large range of air in the vacuum system, thereby promoting reliability under varying conditions of working.

According to the invention a regulated quantity of boiler feed water which is only sufficient to usefully absorb the heat from the steam jet, is admitted to a receiver in which it condenses steam from the steam jet and in which the vapor temperature is maintained higher than the vapor temperature in the condenser whereby the quantity of water required for the condensation of the steam in the receiver is reduced and therefore the pumping power required to discharge such water to the atmosphere is also reduced. The heated water and aerated vapor are delivered separately from the receiver into the ends of one or more barrels of one or more reciprocating pumps on either side of the piston or pistons, or de-

livered into one or more barrels on one side of the piston or pistons, in each case with or without condensate from the condenser, which may be delivered to the pump or pumps direct or through a water seal. When the heated water is withdrawn from the receiver separately at a higher temperature than the aerated vapor, the air pressure or air density of the aerated vapor may be increased by the condensation of the vapor by another portion of the boiler feed water of a temperature lower than that discharged from the receiver, thus decreasing the volume of a given weight of air and reducing the size of the air pump and the power necessary to discharge the air to the atmosphere.

The improved technical effect of apparatus according to the present invention is obtainable both with surface condensers and jet condensers. For example, the quantity of steam used in a steam jet to provide for the removal of a large weight of air may be sufficient to raise the temperature of the whole condensate from the main condenser ten degrees Fahrenheit; consequently, the same quantity of steam would raise one third of the condensate, or one third of the total quantity of the feed water required for the boilers, 30° Fahrenheit. Suppose in a surface condenser the vacuum is 96 per cent. and the vapor temperature is 85° Fahrenheit and that the condensate is withdrawn from the condenser at 75° Fahrenheit by a separate pump. If one third of the total quantity of the condensate at 75° Fahrenheit is led into the steam jet receiver, it will leave the receiver at about 105° Fahrenheit and the temperature of the vapor in the receiver will be maintained at about 110° Fahrenheit. If the aerated vapor from the receiver is brought into direct contact with the condensate at 75° Fahrenheit, the volume of a given weight of saturated air can be reduced from 900 cubic feet per lb. to 200 cubic feet per lb. whereby it can be discharged by an air pump of reduced size and requiring less power, and whereby very high thermal efficiency can be obtained. The same result obtains with a jet condenser carrying a vacuum of say 96 per cent. and a corresponding vapor temperature of 85° Fahrenheit, when the mixture of cooling

water and condensate withdrawn from the condenser, which is about 75° Fahrenheit, is suitable for use as boiler feed water, or when the boiler feed water is supplied from another source.

For steam turbine condensing plant working under very high vacuum, two pumps may be employed, one pump drawing condensate from the condenser in the ordinary way and the other pump drawing aerated vapor from the receiver, the heated water from the receiver being admitted to either or both of the pump barrels between the piston and the discharge valves, so that it is without prejudicial effect on the air withdrawing capacity of the air pump or pumps. By this particular arrangement the water seal which is usually employed in apparatus of this kind between the condenser and the pump, may be dispensed with. Therefore this arrangement may be of great practical advantage on shipboard where the space available for a water seal below the condenser does not usually exceed three or four feet and thereby limits the pressure at which the air pump may withdraw and therefore the amount of air it can deal with.

The accompanying drawings Figures 1 to 8, illustrate various forms of apparatus according to my invention, the same letters of reference being used to denote the similar parts in the several figures.

Aerated vapor is withdrawn from the condenser *c* by a steam jet device *s* discharging into the receiver *r* wherein the steam from the jet is condensed by water such as boiler feed water admitted through the pipe *t*.

In Figs. 2, 3, 4, 5, and 7, a regulated quantity of boiler feed water, which is only sufficient to usefully absorb the heat from the steam jet, is admitted through the valve *g* into the receiver *r* in which it condenses the steam from the steam jet device *s*, and in which receiver the vapor temperature is maintained higher than the vapor temperature in the condenser whereby the quantity of water required for the condensation of the steam in the receiver *r* is reduced and therefore the pumping power required to discharge such water to the atmosphere is also reduced. The heated water is withdrawn from the receiver *r* separately through the pipe *e* at a higher temperature than the aerated vapor which is withdrawn through the pipe *F*, the air pressure of the aerated vapor being increased by the condensation of the vapor by another portion of the boiler feed water admitted through the valve *h* and of a temperature lower than that discharged from the receiver *r* through the pipe *e*, and therefore the temperature of the air delivered to the pump is rendered lower than the temperature of the heated water withdrawn from the receiver *r* through the pipe *e*, thus decreasing the volume of a

given weight of air and reducing the size of the air pump and the power necessary to drive the pump.

In Fig. 1, the heated water is delivered from the receiver *r* through the pipe *e* together with the aerated vapor into that end of the barrel of the reciprocating pump *b* which is situated between the piston and the head valves, and the condensate from the condenser *c* is delivered through the pipe *d* to that end of the barrel of the pump *b* which is situated below the piston, in the usual manner.

In Fig. 2, the condensate is withdrawn from the surface condenser *c* through the pipe *d* by the pump *b* and a portion of the condensate discharged from the pump is delivered from the well *w* through the pipe *t* to the receiver *r* and to the pipe *f* for the purpose hereinbefore described. The aerated vapor is withdrawn from the receiver *r* through the pipe *f* by the pump *a* and enters the end of the barrel below the piston, while the heated water is withdrawn from the receiver *r* through pipe *e* by the same pump *a* and enters the end of the barrel above the piston, thereby tending to balance the water load on both pumps *a* and *b*.

Fig. 3 shows an arrangement by which the pump *a* withdraws aerated vapor alone from the receiver *r* through the pipe *f*, the whole of the heated water from the receiver *r* being admitted through pipe *e* to that end of the barrel of the pump *b* which is above the piston, wherein it mixes with the condensate withdrawn from the condenser through the pipe *d*. In this example both pumps are of the valveless piston type.

Fig. 4 is a modification of Fig. 2, wherein the pump *a* which withdraws the aerated vapor and heated water from the receiver *r*, discharges through the pipe *i* into that end of the barrel of the pump *b* which is between the piston and the discharge valves.

In the arrangements described, the withdrawal of aerated vapor and heated water from the receiver *r* in no way interferes with the removal of condensate from the condenser *c* through the pipe *d*, therefore the arrangements are very advantageous in practice as they obviate the limitations resulting from the use of a water seal between the pump *b* and condenser *c*.

In Fig. 5, aerated vapor and heated water are simultaneously withdrawn from the receiver *r* by the pumps *a* and *b*, the pipe *e* being connected to those ends of both pumps which are above the pistons, and the pipes *f* and *f'* from the receiver being connected to the ends which are below the pistons. In order to prevent the flow of aerated vapor from the pipe *f'* into the pipe *d* and thence into the condenser *c* which is under a lower pressure than the receiver *r*, a water seal *j* is provided, the condensate from the condenser

passing through the seal *j* and into the pump *b* together with aerated vapor from the pipe *f* which is thereby condensed and cooled by contact with the condensate. If desired, the pump *a* may be cooled in a known manner by water in continuous circulation through a water cooler *k*, in which case the supply of water through the valve *h* may be cut off or omitted. Also, both pumps *a* and *b* may be suitably connected together as for example by a valve *v* so that in the event of either pump becoming deranged, the other pump can withdraw the aerated vapor and heated water from the receiver *r* together with the condensate from the condenser *c*, or by opening the valves *o* and *v* both pumps may be employed for withdrawing the aerated vapor and condensate from the condenser *c* without using the steam jet device *s* and the receiver *r*.

In Fig. 6, the pump *b* withdraws heated water, with, it may be, some aerated vapor from the receiver *r* through the pipe *e*, and the condensate from the condenser through the pipe *d*. Aerated vapor is also withdrawn from the receiver *r* by the dry air pump *a*, the water being admitted to the receiver *r* through the valve *g* consisting of condensate supplied from the well *w* into which the pump *b* discharges.

In Fig. 7 which is a modification of Fig. 6, a second receiver *k* forming the air suction system is provided. The heated water from the receiver *r* together with the water and condensed vapor from the receiver *k* are led into a common pipe *e* from which the water flows into that end of the barrel of the pump *b* which is above the piston, the air being removed through the pipe *f* by the dry air pump *a*.

Fig. 8 is a modification of Fig. 5 and in which only one pump *b* is provided. In this example the end of the barrel of the pump *b* which is above the piston receives the aerated vapor through the pipe *f* from the receiver *r*, and the end which is below the piston receives heated water from the receiver *r* through the pipe *e*.

What I claim and desire to secure by Letters Patent is:—

1. Apparatus for withdrawing aerated vapor and condensate from steam condensers, comprising a steam jet device in communication with a condenser, a receiver, and a reciprocating pump, a passage leading from the steam jet to the receiver, a passage leading from a water supply to the receiver, a passage leading from the receiver to the pump, and a passage leading from the condenser to said pump, substantially as and for the purpose herein set forth.

2. Apparatus for withdrawing aerated vapor and condensate from steam condensers, comprising a steam jet device in communication with a condenser, a receiver, and a

reciprocating pump, a passage leading from the steam jet to the receiver, a passage leading from a water supply to the receiver, a passage leading from the receiver to one end of said pump and a passage leading from the condenser to the other end of said pump, substantially as and for the purpose herein set forth.

3. Apparatus for withdrawing aerated vapor and condensate from steam condensers, comprising a steam jet device in communication with a condenser, a receiver, and a reciprocating pump, a passage leading from the steam jet to the receiver, a passage for conveying to the receiver water discharged from said pump, a passage leading from the receiver to the pump, and a passage leading from the condenser to said pump, substantially as and for the purpose herein set forth.

4. Apparatus for withdrawing aerated vapor and condensate from steam condensers, comprising a steam jet device in communication with a condenser, a receiver, and a reciprocating pump, a passage leading from the steam jet to the receiver, a passage for conveying to the receiver water discharged from said pump, a passage leading from the receiver to said pump, a passage leading from the condenser to said pump, and a water seal in the last mentioned passage, substantially as and for the purpose herein set forth.

5. Apparatus for withdrawing aerated vapor and condensate from steam condensers, comprising a steam jet device in communication with a condenser, a receiver, a reciprocating pump, a passage for conveying to the receiver water discharged from said pump, a second pump, a passage leading from the steam jet to the receiver, a passage leading from the receiver to the second pump, a passage leading from the receiver to the first mentioned pump, and a passage leading from the condenser to said latter pump, substantially as and for the purpose herein set forth.

6. Apparatus for withdrawing aerated vapor and condensate from steam condensers, comprising a steam jet device in communication with a condenser, a receiver, two reciprocating pumps, a passage leading from the steam jet to the receiver, passages leading from the receiver to both pumps, a passage leading from the condenser to one of the pumps, and a passage for conveying to the receiver water discharged from said last mentioned pump, substantially as and for the purpose set forth.

7. Apparatus for withdrawing aerated vapor and condensate from steam condensers, comprising a steam jet device in communication with a condenser, a receiver, two reciprocating pumps, a passage leading from the steam jet to the receiver, a passage leading from a water supply to the receiver, sep-

arate passages leading from the receiver to each pump, means for supplying cooled water to one pump, and a passage leading from the condenser to the other pump, substantially as and for the purpose herein set forth.

8. Apparatus for withdrawing aerated vapor and condensate from steam condensers, comprising a steam jet device in communication with a condenser, a receiver, two

10 reciprocating pumps, a passage leading from the steam jet to the receiver, separate passages leading from the receiver to each pump, means for supplying cooled water to one pump, a passage leading from the condenser to the other pump, and a passage for conveying to the receiver water discharged from said last mentioned pump, substantially as and for the purpose herein set forth.

20 9. Apparatus for withdrawing aerated vapor and condensate from steam condensers, comprising a steam jet device in communication with a condenser, a receiver, two reciprocating pumps, a passage leading from the steam jet to the receiver, a passage leading from a water supply to the receiver, separate passages leading from the receiver to one pump, means for supplying cooled water to said last mentioned pump, and a 25 passage leading from the condenser to the other pump, substantially as and for the purpose herein set forth.

10 10. Apparatus for withdrawing aerated vapor and condensate from a steam condenser, comprising a steam jet device in communication with a condenser, a receiver, two reciprocating pumps, a passage leading from the steam jet to the receiver, a passage leading from the receiver to one end of a pump, a passage leading from the lower portion of the receiver to one end of a pump, a passage leading from the condenser to one pump, and a passage for conveying to the receiver water discharged from said last mentioned pump, substantially as and for the purpose herein set forth.

11 11. Apparatus for withdrawing aerated vapor and condensate from a steam condenser, comprising a steam jet device in communication with a condenser, a receiver, two reciprocating pumps, a passage leading from the steam jet to the receiver, a passage leading from the lower portion of the receiver to one end of a pump, a passage leading from the condenser to an end of one pump, a passage leading from the receiver to an end of the other pump, and a passage for conveying to the last mentioned passage and to the receiver water discharged from the pump connected to the condenser, for the purpose herein set forth.

12 12. Apparatus for withdrawing aerated vapor and condensate from a steam condenser, comprising a steam jet device in communication with a condenser, a receiver, a

reciprocating pump, a passage leading from the steam jet to the receiver, a passage leading from the lower portion of the receiver to one end of the pump, a passage leading from the condenser to one end of the pump, a passage leading from the receiver to one end of the pump, and a passage for conveying to the last mentioned passage and to the receiver water discharged from the pump connected to the condenser, for the purpose herein set forth.

13. Apparatus for withdrawing aerated vapor and condensate from steam condensers, comprising a steam jet in communication with a condenser, a receiver, two reciprocating pumps, a passage leading from the steam jet to the receiver, a passage leading from the lower portion of the receiver to one end of each pump, a passage leading from the condenser to an end of one pump, a passage leading from the receiver to an end of the other pump, and a passage for conveying to the last mentioned passage and to the receiver water discharged from the pump connected to the condenser, for the purpose herein set forth.

14. Apparatus for withdrawing aerated vapor and condensate from steam condensers, comprising a steam jet communicating with a condenser, a receiver, two reciprocating pumps, a pipe leading from the steam jet to the receiver, a pipe leading from the bottom of the receiver to one end of each pump, a pipe leading from the condenser to the other end of one of the pumps, a pipe leading from the receiver to the remaining pump end, a well into which discharges the outlet of the pump connected to the condenser, and a pipe for conveying water from the well to the last mentioned pipe and to the receiver, for the purpose set forth.

15. Apparatus for withdrawing aerated vapor and condensate from steam condensers, comprising a steam jet communicating with a condenser, a receiver, two vertical reciprocating pumps, a pipe leading from the steam jet to the receiver, a pipe leading from the bottom of the receiver to the uppermost ends of each pump, a pipe leading from the condenser to one of the lowermost pump ends, a pipe leading from the receiver to the remaining pump end, a well into which discharges the outlet of the pump connected to the condenser, and a pipe for conveying water from the well to the last mentioned pipe and to the receiver, for the purpose herein set forth.

16. Apparatus for withdrawing aerated vapor and condensate from steam condensers, comprising a steam jet communicating with a condenser, a receiver, two vertical reciprocating pumps, a pipe leading from the steam jet to the receiver, a pipe leading from the bottom of the receiver to the uppermost ends of each pump, a pipe leading from the

condenser to one of the lowermost pump ends, a water seal in said pipe, pipes leading from the receiver to the lowermost pump ends, a well into which discharges the outlet of the pump connected to the condenser, and a pipe for conveying water from the well to one of the last mentioned pipes and to the receiver, for the purpose herein set forth.

17. Apparatus for withdrawing aerated vapor and condensate from steam condensers, comprising a steam jet communicating with a condenser, a receiver, two vertical reciprocating pumps, a pipe leading from the steam jet to the receiver, a pipe leading from the bottom of the receiver to the uppermost ends of each pump, a pipe leading from the condenser to one of the lowermost pump ends, a water seal in said pipe, a pipe leading from the receiver to the remaining pump end, a passage between the lowermost ends of the two pumps, a well into which discharges the outlet of the pump connected to the condenser, and a pipe for conveying water from the well to the last mentioned pipe and to the receiver, for the purpose herein set forth.

18. Apparatus for withdrawing aerated vapor and condensate from steam condensers, comprising a steam jet communicating with a condenser, a receiver, two vertical reciprocating pumps, a pipe leading from the steam jet to the receiver, a pipe leading from the bottom of the receiver to the uppermost ends of each pump, a pipe leading from the condenser to one of the lowermost pump ends, a water seal in said pipe, a pipe leading from the receiver to the remaining pump end, a passage between the lowermost ends of the two pumps, a control valve in said passage, a well into which discharges the outlet of the pump connected to the condenser, and a pipe for conveying water from the well to the last mentioned pipe and to the receiver, for the purpose herein set forth.

19. Apparatus for withdrawing aerated vapor and condensate from steam condensers, comprising a steam jet communicating with a condenser, a receiver, two vertical reciprocating pumps, a pipe leading from the steam jet to the receiver, a pipe leading from the bottom of the receiver to the uppermost ends of each pump, a pipe leading from the condenser to one of the lowermost pump ends, a water seal in said pipe, a by-pass control valve for said seal, a pipe leading from the receiver to the remaining pump end, a passage between the lowermost chambers of the two pumps, a control valve in said passage, a well in the discharge outlet of the pump with which the condenser is connected, and a pipe for conveying water from the well to the last mentioned pipe and to the receiver, for the purpose herein set forth.

20. Apparatus for withdrawing aerated vapor and condensate from steam condensers,

comprising a steam jet, a receiver, and a reciprocating pump so arranged that the two ends of its barrel on either side of the piston can be used for the drawing in and subsequent discharge of not less than two of the following fluids namely the condensate from the condenser and the aerated vapor and water from the receiver, one of these three fluids being drawn into one end of the pump, and one or both of the others into the other end, the whole substantially as described.

21. Apparatus for withdrawing aerated vapor and condensate from steam condensers, comprising a steam jet, a receiver, a reciprocating pump, two separate passages for the withdrawal of the aerated vapor and water from the receiver respectively into the two ends of the pump barrel one passage on either side of the piston, a passage for the withdrawal of condensate from the condenser into one of said ends, and a water seal in the passage communicating between the pump and the condenser, the whole substantially as described.

22. Apparatus for withdrawing aerated vapor and condensate from steam condensers, comprising a steam jet, a receiver, a reciprocating pump, another pump, a passage for the withdrawal of the condensate from the condenser into one end of the barrel of the reciprocating pump, a passage for the withdrawal of the aerated vapor from the receiver into the other pump and a separate passage for the withdrawal of water from the receiver into an end of one of the pump barrels other than the ends into which the condensate and aerated vapor are drawn, the whole substantially as described.

23. Apparatus for withdrawing aerated vapor and condensate from steam condensers, comprising a steam jet, a receiver, two reciprocating pumps, a passage for the withdrawal of the condensate from the condenser into one end of the barrel of one pump, a passage for the withdrawal of the aerated vapor from the receiver into an end of the barrel of the second pump, and a separate passage for the withdrawal of the water from the receiver into the remaining ends of both of the pumps, the whole substantially as described.

24. Apparatus for withdrawing aerated vapor and condensate from steam condensers, comprising a steam jet, a receiver, two reciprocating pumps, a passage for the withdrawal of condensate from the condenser into an end of the first pump barrel, a passage for the withdrawal of aerated vapor from the receiver into an end of the second pump barrel, a passage for the introduction of a portion of the condensate after its discharge from the first pump into the receiver for the purpose of cooling the aerated vapor and of cooling and condensing the steam

which enters said receiver from the steam jet, and a passage for the introduction of another portion of the condensate into the passage conveying the aerated vapor to the second pump, the whole substantially as described.

Signed at West Hartlepool, in the county

of Durham, England, this eighteenth day of August 1914.

DONALD BARNES MORISON.
